FIG. 1

To all whom it may concern:

Be it known that we, Harry D. Greenman and Arthur Mund, each citizens of the United States, residing at Englewood and New York, respectively, in the counties of Bergen and Queens, respectively, and States of New Jersey and New York, respectively, have invented a new, original, and ornamental Design for Lazy Suzan, of which the following is a specification, reference being had to the accompanying drawing, forming part thereof.

In the drawing

Fig. 1 is a perspective view of a Lazy Suzan, showing our new design;

Fig. 2 is another perspective view thereof with the tray portions in open position; and

Fig. 3 is a side elevational view thereof.
The back of the Lazy Suzan has the same appearance as the front.

We claim:

The ornamental design for a Lazy Suzan, as shown and described.
